(57) **CLAIM**

The ornamental design for a communications headset, as shown and described.

DESCRIPTION

FIG. 1 is a front right perspective view of the communications headset according to an embodiment.

FIG. 2 is a left back perspective view of the communications headset according to an embodiment.

FIG. 3 is a top down view of the communications headset according to an embodiment.

FIG. 4 is a bottom up view of the communications headset according to an embodiment.

FIG. 5 is a left side view of the communications headset according to an embodiment.

FIG. 6 is a right side view of the communications headset according to an embodiment.

FIG. 7 is a front view of the communications headset according to an embodiment; and,

FIG. 8 is a back view of the communications headset according to an embodiment.

The broken lines showing the ear cushions, wires, wire ports on inside of headband, hexagonal texturing on inside of headband portion, textured holes on outside of headband portion, tension string on right side of headband, tension string clip connected to tension string, tension string pegs, the crisscross raised feature spanning the headband through which the tension string appears to pass, connection ports, and buttons are for the purpose of illustrating portions of the article and form no part of the claimed design.

The thin, black lines show contour of the surfaces of the communications headset, and are not actual lines on the communications headset.
